US0D1073489S

(12) **United States Design Patent** (10) Patent No.: **US D1,073,489 S**
(45) Date of Patent: ** May 6, 2025

(54) **WATCH**

(71) Applicant: **Gerald Charles SA**, Lugano (CH)

(72) Inventor: **Octavio Garcia**, Neuchâtel (CH)

(**) Term: **15 Years**

(21) Appl. No.: **35/520,715**

(22) Filed: **Nov. 3, 2023**

(80) **Hague Agreement Data**

Int. Filing Date: **Nov. 3, 2023**

Int. Reg. No.: **DM/232924**

Int. Reg. Date: **Nov. 3, 2023**

Int. Reg. Pub. Date: **May 3, 2024**

(30) **Foreign Application Priority Data**

May 5, 2023 (CH) 147407

(51) **LOC (15) Cl.** **10-02**

(52) **U.S. Cl.**

USPC **D10/39**

(58) **Field of Classification Search**

USPC D10/30-39, 122-124, 128, 129, 131, 132

CPC G04B 37/005; G04B 37/0058;
